J. S. BURCH

GATHERING MECHANISM

Filed June 16, 1924

FIG. 1

FIG. 2

INVENTOR.

J. Stanley Burch

UNITED STATES PATENT OFFICE.

JOSEPH STANLEY BURCH, OF FRANKLIN, PENNSYLVANIA, ASSIGNOR TO JOY MACHINE COMPANY, OF PITTSBURGH, PENNSYLVANIA.

GATHERING MECHANISM.

Application filed June 16, 1924. Serial No. 720,326.

To all whom it may concern:

Be it known that I, JOSEPH STANLEY BURCH, a citizen of the United States, residing at Franklin, in the county of Venango and State of Pennsylvania, have invented certain new and useful Improvements in Gathering Mechanisms, of which the following is a specification.

This invention relates to certain new and useful improvements in gathering mechanisms for coal loading machines, and more particularly for that class of loading machines adapted to transfer coal from the mine floor to conveniently placed cars for transportation from the mine.

Specifically, the present invention contemplates improvement of the type of gathering mechanism shown, described and claimed in U. S. Letters Patents to Joseph F. Joy, Nos. 1,306,064, dated June 10th, 1919, and 1,445,088 dated Feb. 13th, 1923.

Referring to Fig. 2 of said Letters Patent No. 1,306,064 it will be noted that the guide bar 95, at a certain portion of its movement, encroaches slightly upon the path of the conveyor. At the instant of such encroachment said arm may strike a large chunk of coal and not only shatter the coal but cause an unnecessary strain upon the gathering mechanism; hence it is the object of this invention to eliminate said guide bar and at the same time provide in place thereof an equally efficient construction which will not, at any interval of a cycle of its operation encroach upon the conveyer area. Another object is to provide a gathering mechanism, the forward, material-actuating end of which will describe an orbit or path which is, in general, triangular in shape and in which the substantially straight base of said triangle is the portion of the path whereat the gathering arm is thrust into the material to be actuated.

The construction of my improved gathering mechanism is clearly shown in the accompanying drawings in which:

Fig. 1 is a top plan view, partly broken away, showing the forward end of an inclined loading conveyor provided with a gathering mechanism constructed in accordance with the present invention, and

Fig. 2 is a longitudinal section taken substantially on line 2—2 of Fig. 1.

Referring more in detail to the drawing,

the loading machine in connection with which the present gathering mechanism is used, broadly includes a gathering head or apron —A— carried by the lower forward end of a loading conveyor —B— of the usual and well known chain and scraper type whose foot shaft —5— is driven in the usual manner by the engagement of the sprocket chains of the endless conveyor member, now shown, with the sprocket wheels —6— carried by said shaft —5.

In accordance with the present invention, the hollow head —A— is extended for some distance rearwardly at the sides of the conveyor —B—, and upon the rear ends of these side head extensions are disks —7— that are secured upon the upper ends of upright shafts —8— which are suitably journaled in the head extensions and project upwardly through the top plate of the latter. Secured upon the lower portions of the shafts —8— are spur gears —9— which are disposed within the head extensions and mesh with further spur gears —10— suitably journaled in the head extensions forwardly of the gears —9—. Combined spur and bevel gears —11— are journaled in the gathering head forwardly of the gears —10— and the spur teeth of these gears —11— mesh with the gears —10—, while the bevel teeth thereof mesh with bevel pinions —12— secured upon the opposite ends of the shaft —5—. Thus, when the continuous rotation is imparted to shaft —5—, the disks —7— are caused to continuously rotate in the direction of the arrows —a—.

Each disk —7— is provided with an upwardly extending pivot pin —13— to which is pivoted the rear end of the inner or rear member —14— of a gathering arm. Pivoted on the head extensions for horizontal oscillation are links —15— whose inner ends are pivoted to the members —14— of the gathering arms intermediate their ends. The members —14— are provided at their forward free ends with sockets in which are pivoted the rear ends of fingers —16—, substantially as set forth in the above Patent No. 1,445,088, the pivots for the finger members —16— of the gathering arms being indicated at —17—.

When the shaft —5— is rotated, rotation is imparted to the disks —7— for causing movement of the gathering arms. The

- paths described by the tips of the gathering arm fingers are substantially reniform and as shown by dash lines as at —18—. However, the outer wider portions —18^a— 5 of these paths are substantially straight so that the initial movement of each arm is forward longitudinally in a substantially straight direction for effectively penetrating and loosening the material. The general 10 action and operation obtained is otherwise substantially the same as that set forth in the above patents, but the use of a curved guide bar and a swivelled guide is dispensed with.
- 15 Minor changes may be made without departing from the spirit and scope of the invention as claimed.
- What I claim as new is:
- In a loading machine which comprises 20 among its elements a conveyor organization and a supporting structure for said organization having an apron at the forward,
- receiving end thereof over which the material passes upon its entry to said conveyor; the combination with the foregoing of a 25 gathering mechanism comprising a disc revolvably carried by said apron with its upper face disposed parallel with and adjacent the upper face of said apron, an upwardly-projecting, eccentrically-positioned pin carried 30 by said disc, a gathering arm engaging said pin at the rearward end and having its forward end free and adapted to engage and to sweep material over said apron and upon said conveyor, a link having one of 35 its ends pivotally attached to said arm intermediate its ends and its other end pivotally connected to said apron, and means whereby revoluble motion is transmitted from said conveyor to said disc to actuate 40 said arm.
- In testimony whereof I affix my signature.
- JOSEPH STANLEY BURCH.
